US00D977530S

(12) **United States Design Patent** (10) **Patent No.:** **US D977,530 S**
(45) **Date of Patent:** **** Feb. 7, 2023**

(54) **LARGE SCALE CHILLER**

- (71) Applicant: **Ecodyst, Inc.**, Apex, NC (US)
(72) Inventors: **George Adjabeng**, Apex, NC (US);
Kwabena Williams, Durham, NC (US)
(73) Assignee: **Ecodyst, Inc.**, Apex, NC (US)
(**) Term: **15 Years**
(21) Appl. No.: **29/760,232**
(22) Filed: **Nov. 30, 2020**

(57) **CLAIM**

The ornamental design for a large scale chiller, as shown and described.

DESCRIPTION

FIG. 1 is a front perspective view of the large scale chiller showing our design;

FIG. 2 is a front elevation view of the chiller of FIG. 1;

FIG. 3 is a right side view of the chiller of FIG. 1;

FIG. 4 is a left side view of the chiller of FIG. 1;

FIG. 5 is a rear elevation view of the chiller of FIG. 1;

FIG. 6 is a top plan view of the chiller of FIG. 1; and,

FIG. 7 is a bottom plan view of the chiller of FIG. 1.

The broken lines as shown in the drawings represent environment and form no parts of the claimed design.

1 Claim, 6 Drawing Sheets
